(**) Term: **14 Years**

Primary Examiner — Michael A Pratt

(21) Appl. No.: **29/506,579**

(74) *Attorney, Agent, or Firm* — Haugen Law Firm PLLP

(22) Filed: **Oct. 17, 2014**

CLAIM

(51) **LOC (10) Cl.** **12-16**

The ornamental design for a suspension spacer, as shown and described.

(52) **U.S. Cl.**

USPC **D12/159**

(58) **Field of Classification Search**

DESCRIPTION

USPC D12/159-160

CPC B60G 2204/4402

See application file for complete search history.

(56) **References Cited**

FIG. 1 is a front, right, perspective view of the suspension spacer of the present invention;
